UNITED STATES PATENT OFFICE.

JONATHAN O. FOWLER, OF NEW YORK, N. Y.

SAFETY-TREAD.

1,169,074.

Specification of Letters Patent.

Patented Jan. 18, 1916.

Application filed October 25, 1910. Serial No. 588,995.

To all whom it may concern:

Be it known that I, JONATHAN O. FOWLER, a citizen of the United States of America, and a resident of New York, in the county 5 and State of New York, have invented a certain new and useful Safety-Tread, of which the following is a specification, the same being a full, clear, and exact description of the device, such as will enable others skilled in 10 the art to which it appertains to make and use the same.

This invention relates to non-slipping devices and particularly to sandals or horse-overshoes, or hoof attachments for horses or 15 other animals, designed to afford a firm footing or secure hold in places where the smoothness of the surface is such as to cause slipping or sliding, or to render a grip or solid hold difficult.

20 An object of the invention is to provide a substantial and durable attachment, detachable from the foot, and adapted to inclose the hoof, and comprising at least one detachable or disconnectible member having a longitudinal and transverse series of contact 25 points or retaining edges or faces adapted to engage a smooth surface with a friction contact, and to penetrate or cut into ice or snow, and thereby afford a firm grip or footing.

30 Additional objects of the invention will be apparent in the further description of the invention setting forth devices of the character described, the same being of simple construction, and forming in operation a 35 durable and efficient organization.

To attain the desired end the invention consists in novel devices and combinations of devices as hereinafter explained.

In order to enable the invention to be more 40 clearly understood I shall proceed to explain the same by reference to the drawings which accompany and form a part of this specification, and in which—

45 Figure 1 is a bottom view of the hoof showing my device applied thereon; Fig. 2 is a side view of the same; Figs. 3 and 4 and Figs. 5, 6 and 7 are respectively views in detail of separable calk supports constructed according to my invention; Fig. 8 50 is a bottom view of the hoof illustrating another device constructed according to my invention applied thereon; Fig. 9 is a side view of the same; and Fig. 10 is another bot-

tom view of the hoof showing still another device embodying my invention applied 55 thereon.

Like letters and numerals of reference indicate like parts in all the views.

Referring particularly by reference characters or symbols to the drawings. A denotes 60 the foot of a horse, B a horse shoe which may be of any suitable or approved construction, and C the protecting detachable attachment, or sandal, or overshoe. The arrangement of the sandal is preferably such that 65 the frog will not be injured as the center of the hoof is not covered, and, as the working parts of the overshoe lie adjacent to the metal horse shoe, no corns can result from its use. The said sandal or overshoe provides 70 a separable tread preferably located at least at the toe of the foot, and comprising a calk preferably detachable from the tread and preferably formed with a plurality of contact faces which in use may be respectively angularly disposed; and a preferably detachable holder for the calk comprising (1) a preferably separable support for the calk and tread holding means lying over the shoe and passing up onto the hoof, and (2) 75 80 calk positioning means lying at one side of a calk contact face and independent thereof, and detachable therefrom, to keep the calk in operative position, and also means for attachment of the tread to the hoof, as will be 85 more fully set forth below.

My safety-tread provides one or more calk-holders comprising two members, namely, calk supports proper, as D, and tread holding means, as links E, F, and E, 90 F', L, the said calk-holders being either of sectional construction, as shown in Figs. 1 and 2, or integral in conformation, as illustrated in Figs. 8 and 9, as 1, 2, 3 and 4.

The calks may be either of single unitary 95 construction, as the links J, having a single contact face, or of plural conformation, as spaced calks, or a calk having a plurality of spaced contact faces of opposing inclinations, as for example one made in the form 100 of a coil, as J'. The calk supports, as D, are preferably made of duplex construction and of varying thickness, as for example, those illustrated in Figs. 5 to 7 where the two members d' d'', of the supports D 105 may have a slot at either end, the said slots

opening in opposite directions and arranged so that when the said members are assembled, that portion of the calk holder comprising the links E may be held therebetween and the whole kept detachably fastened together by attaching thereto suitable independent calk positioning devices, as the detachable rivets *j*, which latter elements lie at one side of a calk contact face and are separable therefrom and preferably serve to detachably secure the calk and calk support together and to hold the whole device together as an entirety and the calk in operative position at will, and to prevent it from being forced out of the same by the pounding of the horse's foot. Or, if preferred, the calk support D may consist of two members *d*³, *d*⁴, as shown in Figs. 3 and 4, curved in opposite directions at their central portions so as to loosely hold in the opening formed by said concave bends that portion of the calk-holder comprising the links E or, if preferred, the calk holders 1, 2, 3 and 4 in Figs. 8 to 10. After the parts are assembled, calks, as J, may be slipped over the members *d*³, *d*⁴ and the parts held in position by suitable means, as rivets *j*, the whole support in this case being practically integral.

Owing to the preferred looseness of the connections between the parts D and E, the adjacent projecting longitudinal and transverse retaining portions, or series or contact points of the same, shown at J', *d* and *e* in Fig. 1, will lie at somewhat different angles relative to each other each time the animal steps on the ground, the angular difference of the lines of said contact points, or the opposing portions of the said longitudinal retaining contact points, serving to form a grip and to obstruct the lateral movements of the calks and to force them against the positioning means and to produce an increased cramping or friction effect which tends to prevent any slipping or sliding of the sandal or overshoe either when two spaced calks, as J, or when two spaced portions or contact faces of the same calk, as J', are used, in which latter case any considerable movement of the parts is not necessary, the same being dependent upon the tightness of the adjustment of the hoof attachment means.

The parts of my sandal or overshoe are preferably arranged in the general shape of a horse shoe and the calk-holding device is held on the hoof of the horse by that part of the same comprising a suitable tread holding means made either integrally or of sectional construction and lying over the shoe and passing up onto the hoof, as a link or series of links E, F, and E', F', which front calk holding means E, F may preferably be secured to bands, as G, forming hoof attachment means, ordinarily con-

structed of flexible material, and the rear tread holding means E, F' may ordinarily be secured to the said band G and also to the hoof attachment means comprising the band G' which is preferably cushioned as by being covered with leather or rubber and passes across the rear of the hoof and secured from downward displacement by resting against the metal horse shoe. The free ends of the front calk-holding means may also be held in position by the hoof attachment means comprising a band, as H, having a buckle of suitable description and passing across the front of the hoof. The parts G, G' and H may be made either of thin sheet metal or woven fabric.

From the above description it will be noted that the detachable and replaceable calks, as J, J' are ordinarily used in connection with a detachable calk-holding device comprising calk support and tread holding members, which may be integral, and also with a detachable calk positioning means, as *j*, lying at one side of the calk and separate therefrom, to secure the calk and calk-holding devices together, and that the said entire tread is held in place by hoof attachment means.

It will be seen that the calk positioning means is located exterior, and lies at one side, of a calk contact face, but independent thereof, to prevent lateral movement of the calk along the longitudinal axes of the holder and contact of the calk, and that it also has means to engage and disengage the tread at will to afford retaining means to secure together both the holder and the calk in operative position, when engaged with the tread, and the whole device together as an entirety.

In Figs. 8 to 10 the safety-tread is represented as comprising calk-holding devices consisting of a plurality of integral heavy round wire hooks, as 1, 2, 3 and 4, connected together by means of two links 5 and 6, as in Fig. 10, which preferably cross each other. The hooks 1, 2, 3 and 4 are constructed and arranged to be interposed between the foot of the animal and the ground and to be turned upward over the hoof. At the point where the said hooks turn upwardly I provide positioning means, as for example the use of nuts or washers 7, or by widening the said hooks thereat, for keeping the calks 8 in operative working condition. The calks 8 are sometimes made loose or disconnected from and relatively movable as regards each other. Owing, in such cases, to the looseness of the elongated calks the several series of contact points or contact faces of the same will lie at somewhat different angles relative to each other each time the animal steps on the ground, a cramping or friction effect to prevent slipping being obtained thereby, al-

though any considerable movement of the said parts is not essential to the operation of the other parts of the invention as was stated in regard to the elongated links J, J'. The calks 8 may be readily detached from the hooks which support the same by opening the loops on the ends of the said hooks. If preferred, the ends of the links 5 and 6 may, instead of crossing each other, extend from one forward hook, as 1 or 2, to the rear hook, as 3 or 4, as is shown by the parts 5^a and 6^a. The upper portions of the hooks 1 and 2 are preferably made in loop form through which the hoof attachment means 15 comprising a strap or band, as 9, preferably made of woven fabric or leather, is passed, which band is ordinarily fastened to the upper portions of the hooks 1 and 2, and the free ends of the latter, as 1^a, which 20 may extend either in an upward or downward direction, may be connected with the hoof attachment means in the ordinary manner by fabrics or by the means of a band 10 which may serve to tie the parts 1 and 2 together, the extreme end of the band 10 being secured to a buckle 11. The hooks 2 and 4 may be connected by a link 12 and the hooks 1 and 3 by a link 13, which links may cross each other, the hooks 1 and 2 being 30 also in that case preferably connected by a link 14. Or the longitudinally disposed links may be arranged so as not to cross each other as shown at 12^a and 13^a in Fig. 8. In this latter embodiment of the invention the 35 calks are designated by the numeral 8, which calks provide spaced contact faces, which may obviously be of integral construction, as for example, being made in the manner illustrated in Figs. 1 and 2 at J', wherefore 40 the calks may be provided with either a single contact face, as J, or with dual or plural spaced contact faces, as J', or with multiple spaced contact faces, as 8. In the embodiment last described the members of the 45 calk-holding device comprising the calk supporting means and the tread holding means are of integral construction, wherefore the said calk-holding device may be either of sectional construction, as the parts 50 D, E, F or D, E, F' in Figs. 1 and 2, or they may be of integral conformation, as the parts 1, 2, 3 and 4 in Figs. 8 to 10. The number of the calks and also of the calk-holding devices may be reduced as may be 55 desired in order to make the tread of lighter weight and of simpler construction. The calk positioning means is shown in Figs. 1 to 7 as the rivet j and in Figs. 8 to 10 as the nut 7, in both of which cases it is independent of the calk-holder before being attached to the same and is also detachable at will. The calk-holding device denoted by the characters F, E, D, L, F', and that also denoted by the characters 1, 13, 3, extends 60 in an irregular line from one side of the

hoof attachment means to the other, in both of which instances the calks J' and 8 are supported by the same under the shoe.

The coils J' comprise a plurality of convolutions which are relatively movable and 70 yieldable. In instances where oppositely disposed movable coils J' are employed as calks in lieu of the plurality of rings shown at 8 in Fig. 10, the action of the horse in first putting his toe to the ground to obtain 75 a foothold and then in exerting a strain on the safety tread in a relatively backward direction will, due to the friction between the calks and the ground, tend to compress the convolutions of the sidewise disposed 80 front coils 8, which action will somewhat move them relatively forward on their support so far as the limiting positioning means will permit, and somewhat increase the distance between the latter and the practically 85 alined rear coils 8. Upon raising his foot again, the said convolutions will exert a reactive force against the positioning means owing to the removal of the strain upon them and will again resume their normal 90 positions.

It will be noted in this connection that in all of the figures a continuous metallic connecting means extends between the calks and the hoof attachment means, and in 95 Figs. 8 to 10 the calks are secured to the hoof attachment means by means of intermediate integral wire calk-holding devices comprising the hooks 1, 2, 3 and 4. Obviously, any parts of either embodiment of the 100 invention described may be substituted for similar operating parts in the other embodiment, the invention consisting in this particular of a metallic calk-holder extending downward from the hoof attachment means 105 at one side of the foot, across the hoof, and upward again at the opposite side of the latter, providing at least one strand having a sort of U-shaped conformation and supporting at approximately the central part 110 thereof a calk having spaced and opposing, or non-alined, contact faces. Additional calk supporting means may be used in conjunction with that referred to, as for example, with the calk-holder or tension strand F, E, 115 D, L, F', extending across the hoof, a metallic connection between the calk and hoof attachment, as the strand comprising the parts E, F, intermediate the ends of the other strand, may be employed; and with the tension strand 1, 13, 3, extending across the hoof, a metallic connection between the calk and hoof attachment means, as the strand 14, 2, intermediate the ends of the other strand, may be employed. 120

The calk supports D and also the loops at the ends of the hooks 1, 2, 3 and 4 may also serve to afford additional friction means, or contact faces, and to that extent they also may serve to act as calks. The 125 130

elongated ring calks J, J' and 8 are not claimed specifically in this application, as they are claimed in a continuing application hereof filed Oct. 15, 1912, Serial No. 725,783.

I wish it to be understood that I do not desire to be limited to the exact details of construction shown and described, for obvious modifications will occur to a person skilled in the art.

What I claim as my invention is:

1. In an overshoe of the class described, a separable safety tread comprising the following elements: a non-slipping calk to bear upon and act in coöperation with the tread portion and having means to engage and disengage the same at will, means for attachment of the tread to the hoof, an intermediate holder for the calk having means to engage and disengage both the calk and hoof attachment means at will, and calk positioning means located exterior and lying at one side of a calk contact face to prevent movement of the calk and to engage and disengage the tread at will and to secure the calk and holder in operative position.

2. In an overshoe of the class described, a separable safety tread comprising the following elements: a non-slipping calk to bear upon and act in coöperation with the tread portion and having means to engage and disengage the same at will, means for attachment of the tread to the hoof, an intermediate holder for the calk lying across the toe of the hoof and having means to engage both the calk and hoof attachment means, and calk positioning means located exterior and lying at one side of a calk contact face and having means to prevent movement of the calk and to engage and disengage the tread at will and to secure the device together in operative position as an entirety.

3. In an overshoe of the class described, a non-slipping calk having a plurality of spaced and non-alined contact faces and arranged to bear upon and act in coöperation with the tread portion and having means to engage and disengage the same at will, means for attachment of the tread to the hoof, an intermediate holder for the calk having means to engage both the calk and hoof attachment means at will, and calk positioning means located exterior and lying at one side of a calk contact face to engage and disengage the tread at will and to secure the device together in operative position as an entirety.

4. In an overshoe of the class described, a non-slipping calk having a plurality of contact faces and arranged to bear upon and to act in coöperation with the tread portion and having means to engage and disengage the same at will, means for attachment of the tread to the hoof, an intermediate holder for the calk lying across the toe of the hoof and

having means to engage both the calk and hoof attachment means at will, and calk positioning means located exterior and lying at one side of a calk contact face and having means to prevent movement of the calk, and to engage and disengage the tread at will, and to secure the device together in operative position as an entirety.

5. In an overshoe of the class described, a non-slipping calk to bear upon and act in coöperation with the tread portion and having means to engage and disengage the same at will, hoof attachment means, intermediate metallic calk holding means comprising a support for the calk lying under the hoof and tread holding means passing up over a part of the hoof intermediate the calk and hoof attachment means and having means to engage both of the same, calk positioning means located exterior and lying at one side of a calk contact face to engage and disengage the tread at will.

6. In an overshoe of the class described, a tread portion comprising an attachable and detachable calk, hoof attachment means, metallic calk holding means extending in an irregular U-shaped line from each side of the hoof attachment means toward the other to support the calk at the toe of the hoof under the shoe and attachable to and detachable from the calk and hoof attachment means, and attachable and detachable calk positioning means located exterior and lying at one side of a calk contact face but independent thereof and having means to engage and disengage the tread at will to afford retaining means to secure the calk in operative position, when engaged with the tread, and the device together as an entirety.

7. In an overshoe of the class described, a tread portion comprising an attachable and detachable calk, hoof attachment means, metallic calk holding means extending in an irregular line in substantial U-shape from each side of the hoof attachment means toward the other and also supporting the calk at substantially the central portion thereof under the hoof and attachable to and detachable from the calk and hoof attachment means, in combination with an additional supporting means located intermediate the calk and the ends of the first named calk holding means, and with calk positioning means lying at one side of a contact face to hold the device together as an entirety.

8. In an overshoe of the class described, a separable safety tread comprising the following elements: a non-slipping calk to bear upon and act in coöperation with the tread portion and having means to engage and disengage the same at will, means for attachment of the tread to the hoof, an intermediate holder for the calk located adjacent

to and under the forward part of the hoof and having means to engage and disengage both the calk and hoof attachment means at will, and calk positioning means located exterior and lying at one side of a calk contact face to engage and disengage the tread at will and to secure the calk and holder in operative position, in combination with supplemental calk contact faces supported by 5 the said holder so as to lie adjacent to the rear portion of the hoof.

9. In an overshoe of the class described, a separable safety-tread comprising the following elements: a non-slipping calk to 10 bear upon and act in coöperation with the tread portion and having means to engage and disengage the same at will, means for attachment of the tread to the hoof, an intermediate holder for the calk comprising a 15

plurality of connected sections lying across 20 the toe of the hoof and having means to engage both the calk and hoof attachment means, and calk positioning means located exterior and lying at one side of a calk contact face and having means to prevent movement of the calk and to engage and disengage the tread at will and to secure the device together in operative position as an entirety.

In testimony of the foregoing specification I do hereby sign the same in the city of New York, county and State of New York, this 24th day of September, 1910.

JONATHAN O. FOWLER.
